[57] CLAIM

The ornamental design for a float device with removable insert, as shown and described.

DESCRIPTION

FIG. 1 is a top perspective view of a float device with removable insert showing my new design with the insert removed;

FIG. 2 is a top plan view thereof;

FIG. 3 is a left side elevational view thereof, the right side elevational view being a mirror image;

FIG. 4 is a front end elevational view thereof, the rear end elevational view being a mirror image; and,

FIG. 5 is a bottom plan view thereof.

The removable insert is shown installed in FIGS. 2 through 5.
